PAUL N. COATES, OF ST. PAUL, MINNESOTA

GOLF SCORING DEVICE

Application filed October 6, 1930. Serial No. 486,604.

The present invention relates to a golf scoring and recording device.

In the playing of golf, particularly in tournament play, it is desirable to know the standings of the different players and also their location on the golf course.

An object of the present invention is to make a mechanism with members adapted for marking the scores of individual players thereon arranged to travel along an indexed path indicating the various holes of the golf course with the par score at each hole indicated thereon.

In order to attain this object, there is provided, in accordance with one feature of the invention, a score board having the holes of the course indicated thereon by number and separated from each other by equally spaced index markings, each of which indicates one shot in the par score for each of said holes. A plurality of score indicating members are provided and are adapted to overlie the face of the score board, each of said members being formed with a pointer pointing toward the indexed units on the board. A traveling conveying mechanism is mounted on the board and may be connected to the score indicating members to move them along the score board at a uniform rate of speed corresponding to the estimated normal amount of time required to play the course.

Of course, there is a wide variation in the amount of time required to play a course by a poor player and a good player, but, in tournament play, all of the players progress along the course at a remarkably uniform rate of speed and it is this feature which permits the use of such a board as is illustrated and described herein.

In the accompany drawing:

Figure 1 is a view in front elevation of a device embodying the present invention, with a plurality of score indicating members mounted thereon.

Figure 2 is a top view of the mechanism shown in Figure 1.

Figure 3 is a rear view of the structure shown in Figures 1 and 2 with a housing and drive unit for a conveyor chain removed,

the position of the housing being indicated in dotted lines.

Figure 4 is an enlarged sectional view on the line 4—4 of Figure 1, the lower portion thereof being broken away to permit increasing the scale of the drawing; and

Figure 5 is a view in front elevation of an indicating marker, the lower portion thereof being broken away.

Referring to the drawing in detail, the score board itself comprises an elongated strip A formed of wood or other suitable material. A channeled track 1 is secured to the rear face of the board A adjacent the upper edge thereof.

A chain 2 is mounted to lie in this channeled track and runs over idling wheels 3 and 4 positioned at each end of the channeled track 1, over idling wheels 5 and 6 and under a drive sprocket 7 which is driven by suitable motive power, such as an electrical motor, through reduction gears or by clockwork. The sprocket 7 is removably connected to its supporting shaft and may be replaced by larger or smaller sprockets in a well known manner to vary the speed of the conveyor chain 2. The motor drive mechanism is also provided with speed control mechanism such as a rheostat in the case of an electric motor and a variable governor in the case of a clockwork mechanism. Neither of these driving mechanisms are illustrated in detail, as they are both well known to the art as well as other controlled variable speed drive mechanisms which would be suitable for the intended use. The drive sprocket 7 is driven by said suitable variable speed mechanism to move the chain 2 at any suitable speed, the speed being determined by the amount of time it is desired to occupy in moving individual scoring members B from one end of the board A to the other.

If the board is to be used in recording two-some plays, the speed of the conveyor chain 2 will be adjusted so as to move the scoring members B faster than is the case where the play is to be by threesomes or foursomes, since it is apparent that it takes a threesome longer to play the course than a twosome and a foursome longer than a threesome. The

speed of the conveyor chain may be varied during the progress of play as above set forth to conform to the average progress of the players over the course.

- 5 The position of the driving mechanism 8 is indicated in Figures 2 and 3. A plurality of individual scoring plates B are formed as from sheet metal with a planiform front portion 9, the lower part of which is preferably shaped to a point as at 10, and is coated with a suitable material to permit writing thereon, such as blackboard paint. The face of this portion is then divided by lines, as illustrated, to provide a space for the players' names and spaces for the marking of the scores. The upper portion of the plate is bent at right angles as at 11 for a distance greater than the thickness of the board A and then downwardly at right angles as at 12 and rearwardly again at right angles as at 13. A pair of pins 14 are mounted in this rearwardly bent portion 13 of a size to enter the openings in the links of the chain 2.
- 25 In using the device the mechanism is set in motion and the speed of the belt is timed so that the time of travel of one point of the belt from one end of the channel 1 to the other is the estimated time required to play the course.

Assuming that a tournament is to be played by twosomes, which is the customary way of playing in tournament, the names of the first pair of players are written on one of the plates in the space provided therefor, as in Figure 5, and, as the first player of this twosome tees off, the plate is set in position with the pins 14 inserted in the openings in the chain 2. As the first twosome completes the first hole their score for this hole is either phoned in or is brought in by runners. It is customary to have one field telephone located at every third or fourth hole, although in important tournaments a telephone is sometimes provided at each hole so that the score of the players is transmitted to the score board for each hole, as it is played. The score is preferably recorded as illustrated, namely, by recording the number above or below par at the particular hole played.

As the next twosome is ready, their names are inscribed on a second plate B, and, as the first player of this twosome tees off, the plate 55 for this pair is placed in position on the board in the same manner as for the first. It is very seldom in tournament play that anyone plays through another group of players, however, in case this should occur, the positions of the plates on the board may be readily adjusted at any time to indicate the true location of the players on the course.

In the board illustrated in Figure 1, there are eight twosomes on the course. The first 65 pair out, indicated by the right hand marker,

have almost completed the course. The names of these two players are Rice and Tate. A glance at the board indicates that they have almost finished the eighteenth hole and that Rice is seven over par and Tate was one under par at the seventeenth hole. As the par score at each hole is inscribed on the board their scores are readily calculated from this. The last pair out are Smith and Diegel. They have just finished the first hole, and Smith is one under par and Diegel is par.

In case a spectator cares to follow the game from the score board, he may watch the recording of the progress of the players around the course and thus obtain a clear mental picture of the entire match. If one prefers to go out on the course, however, and watch any particular pair of players, a glance at the score board will immediately indicate what hole such players are on and what their respective scores were at the last hole played.

The device provides a simple and effective mechanism for recording the score of the various players and as the plates travel along keeping proportionate pace with the travel of the players around the course it assists greatly in following the game and the progress of the players around the course and facilitates spectators in locating the players which they wish to follow on the course.

I claim:

1. A golf score display mechanism, comprising a member having a plurality of uniformly spaced indexed markings on the face thereof, said markings being divided into groups, each group being the number of strokes in the par score of a hole on a golf course, said groups being successively marked with the numbers of the holes of said golf course, a conveying mechanism associated with said member, drive means connected to said conveying mechanism to drive said conveying mechanism at a predetermined speed to conform in proportion to the rate of travel of a player on a golf links and a plurality of marking plates slidably mounted to overlie said board and removably connected to said conveying means, each of said plates having a space thereon for the names of players and a space thereon for the marking of the players' scores thereon.

2. A golf score display mechanism, comprising an indexed member marked to indicate the par strokes of a golf course, indicating means mounted adjacent said indexed markings on said index member, and conveying means adapted to be removably connected to said indicating means to move said indicating means at a controlled speed along said indexed member.

3. A golf score display mechanism, comprising means having a plurality of uniformly spaced indexed markings thereon to indicate the par strokes of a golf course, indi-

cating means having a portion thereof adjacent the indexed markings on said first means, and controlled power driven means to cause a relative movement between said indexed means and said indicating means in proportion to the estimated speed of travel of a player over a golf course.

4. A golf score display mechanism comprising a member having a plurality of uniformly spaced indexed markings on the face thereof, said markings being divided into groups, each group being the number of strokes in the par score of a hole on a golf course, said groups being successively marked with the numbers of the holes of said golf course, conveying means mounted adjacent said indexed member, traveling longitudinally thereof at a speed estimated to move the space of one group in the estimated time required for the tournament golf player to play one hole on a known golf course, an indicator adapted to be removably connected to said conveyor to overlie the portion of said board bearing said indexed markings and having a pointer thereon pointing toward said indexed markings, said indicator being adapted to be inscribed with the name and score of a player.

30 In testimony whereof I affix my signature.
